No. 874,473.

PATENTED DEC. 24, 1907.

N. J. WINLUND.
DULCIMER ACTION.
APPLICATION FILED JULY 30, 1907.

UNITED STATES PATENT OFFICE.

NICHOLAS J. WINLUND, OF ROCKFORD, ILLINOIS.

DULCIMER-ACTION.

No. 874,473.

Specification of Letters Patent.

Patented Dec. 24, 1907.

Application filed July 30, 1907. Serial No. 386,296.

To all whom it may concern:

Be it known that I, NICHOLAS J. WINLUND, a citizen of the United States of America, residing at Rockford, in the county of Winnebago and State of Illinois, have invented certain new and useful Improvements in Dulcimer-Actions, of which the following is a specification.

The object of my invention is to provide an action adapted for use in performing on the dulcimer; and it consists of certain new and useful features of construction and combinations of parts especially devised to that end, all as hereinafter fully described and 15 specifically pointed out in the claim appended hereto.

Referring to the accompanying drawings, which form a part of this specification, Figure 1 is a longitudinal vertical section of a dulcimer provided with my improvement. Fig. 2 is a section, at the dotted line 2—2 in Fig. 1, of parts there shown. Fig. 3 is a section, at the dotted line 3—3 in Fig. 1, of parts there shown.

Like reference characters indicate corresponding parts throughout the several views.

1 is the body of the dulcimer and is of the usual box-like form having bridges 2 and 3 seated on its sounding board 4 and provided 30 with strings 5 stretched across the bridges and attached to retaining and tuning pins 6 and 7 in the usual manner.

8 is a key-rail and 9 a hammer-rail, the latter having transverse slots 10 formed in its 35 upper edge portion for a purpose to be explained hereinafter. The two rails constitute the main support of the action as well as a portion of the case for inclosing the same.

11 is a bar having guide-slots 12 extending 40 therethrough and is secured by its ends to the end-pieces (not shown) of the action case.

13 is a key having a spring-chamber 14 formed therein and provided with a hinge-slot 15 extending vertically therethrough.

45 16 is a hinge-pin seated in the key-rail 8 and passing through the slot 15 in the key 13 and forming therewith a hinge for said key.

17 is a hammer provided with a stem 18 the free end whereof rests in one of the trans- 50 verse slots 10 in the rail 9.

19 is a guide-pin seated in the key 13 and projecting downward therefrom through guide-slots 20 and 21 in the hammer stem 18 and bar 11.

55 22 is a spring within the chamber 14, in the key 13, and connects and normally maintains

the hammer 17 and its stem 18 in close contact with the under side of said key. Acting against the resistance of the rails 8 and 9 said spring also normally maintains the key 13 at 60 its upper limit of travel.

23 is a felt pad fast to the stem 18 of the hammer 17 and serves to render the contact between said parts and the key 13 noiseless, while the same are being operated. 65

24 is an adjusting-screw turned into the bar 11 and its function is to limit the downward travel of the hammer 17 and its stem 18. The adjusting - screw 24 should be turned upward sufficiently to prevent the 70 hammer 17 from resting on the wire 5. As it descends its momentum will flex its stem, as it strikes said adjusting-screw, sufficiently to cause it to strike the wire, and the resiliency of said stem will immediately thereafter 75 lift such hammer out of contact therewith and thereby leave it free to vibrate.

25 is a felt pad fast to the under side of the hammer-stem 18 and serves to render the contact between the latter and the adjusting- 80 screw 24 noiseless.

26 is the back of the case and is fast to the rail 8.

27 is the center support of the case and rests upon blocks 28 at the ends thereof. 85

29 and 30 are hinged together at 31 to form the cover of the case and the former is hinged to the back 26 at 32.

33 is a closure for the space between the 90 ends of the keys 13 and the rail 9.

If one of the keys 13 be struck in the usual manner its front end will tilt downward and, acting upon and through the stem 18 of the hammer 17, will also force them downward until the former strikes the regulating-screw 95 24, the force of the impulse continuing until the hammer 17 strikes the wire 5, as indicated by dotted lines in Fig. 1. The resiliency of the stem will immediately thereafter start said hammer 17 upward, and the spring 100 22 will cause the same and the key 13 to continue their upward movements, until they assume their original positions, as indicated by solid lines in Fig. 1.

What I claim as new, and desire to secure 105 by Letters Patent, is—

1. In combination, a key, a hammer and its stem and a spring connecting and normally maintaining the hammer and stem in close contact with the under side of the key, 110 substantially as described.

2. In combination, a key-rail, a key mount-

ed thereon, a hammer-rail, a hammer mounted thereon by means of its stem and a spring connecting and normally maintaining the hammer and its stem in close contact with
5 the under side of the key, and said key at its upper limit of travel, substantially as described.

3. In combination, a key-rail, a key mounted thereon, a hammer-rail, a hammer mounted thereon by means of its stem, a spring connecting and normally maintaining the hammer and its stem in close contact with
10

the under side of the key and said key at its upper limit of travel and an adjusting-screw for limiting the downward travel of the hammer and its stem, substantially as described. ¹⁵

In testimony whereof I have signed my name to this specification in the presence of two subscribing witnesses.

NICHOLAS J. WINLUND.
